(57) **CLAIM**

The ornamental design for a cover for electronic device, as shown and described.

DESCRIPTION

FIG. 1 is a front, top, and right sides perspective view of a cover for electronic device, showing my design;
 FIG. 2 is a front view thereof;
 FIG. 3 is a back view thereof;
 FIG. 4 is a left side view thereof;
 FIG. 5 is a right side view thereof;
 FIG. 6 is a top view thereof;
 FIG. 7 is a bottom view thereof;
 FIG. 8 is a back, top, and left sides perspective view thereof; and,
 FIG. 9 is a front, bottom, and left sides view thereof.
 The broken lines shown in FIGS. 3 and 8 depict inner parts of the cover for electronic device and form no part of the claimed design.

1 Claim, 4 Drawing Sheets(56)
